UNITED STATES PATENT OFFICE.

WILLIAM F. LAUGHRAN AND FRANK C. ALARIE, OF TROY, NEW YORK, ASSIGNEES OF
ONE-THIRD TO WILLIAM A. LEE, OF TROY, NEW YORK.

SPARK-PLUG.

1,318,391.

Specification of Letters Patent. Patented Oct. 14, 1919.

Application filed July 18, 1916. Serial No. 109,874.

To all whom it may concern:

Be it known that we, WILLIAM F. LAUGHRAN and FRANK C. ALARIE, citizens of the United States, residing at Troy, county of 5 Rensselaer, and State of New York, have invented certain new and useful Improvements in Spark-Plugs, of which the following is a specification.

Reference may be had to the accompanying drawings, and the reference characters marked thereon, which form a part of this specification. Similar characters refer to similar parts in the several figures therein.

The principal object of the invention is 15 to effectively test the action of a spark-plug while in use.

Figure 1 of the drawings is a view in side elevation of a spark-plug embodying our invention.

20 Fig. 2 is a central cross-section taken through the axis of the plug.

Referring to the drawings wherein the invention is shown in preferred form, 1, is a wire-holder made of porcelain or other insulating material containing two wires 2 and 3, terminating in adjacent points at the inner end of the plug at 4.

The wire-holder 1, is mounted within a casing formed by a sleeve 5, and a bushing 6, screwed into the outer end of the sleeve 5.

The inner end 7 of the sleeve is screw-threaded to fit a similarly threaded spark-plug-aperture in an engine-casing 8, in connection with the ground side 9, of an electric circuit.

The wire-holder has an annular shoulder 10, which is engaged by the bushing 6, to securely clamp the wire-holder in position 40 within the wire-holder-casing.

The wire 2, extends entirely through the wire-holder 1, and has an outwardly projecting end 11, adapted to be connected with the other side 12, of said electric circuit.

45 The wire 3, extends only part-way longitudinally through the wire-holder, and has its outer end 13, projecting laterally through, and exposed upon one side of, the wire-holder outside of the wire-holder-casing.

A metal sleeve 14, is slidably mounted upon the wire-holder 1, outside of the wire-holder-casing, and in contact with the laterally projecting end 13 of the wire 3.

55 The sleeve 14, has a handle 15, fixed

thereon, whereby it can be adjustably moved toward and from the bushing 6, forming part of the wire-holder-casing, which adjustment may be accomplished by a direct movement of the sleeve longitudinally of 60 the wire-holder, or by a spiral movement of the sleeve.

The sleeve has on its inner end a contact-point 16, which can by such adjustment of the sleeve be brought into contact or engagement with the bushing 6, or more or less separated from the bushing 6.

In the normal operation of the plug the sleeve 14, is adjusted with its contact-point 70 16, bearing against the bushing 6, thus electrically connecting the wire 3, through the sleeve 14, bushing 6 and sleeve 5, with the engine casing 8, which is in electrical connection with the ground side 9, of the electric circuit.

75 When it is desired to test the action of the plug, the sleeve 14, is moved slightly outward, along the wire-holder 1, until its contact-point 16, is slightly separated from the bushing 6, whereupon if the plug is in proper working condition a spark will be seen between the contact-point 16, and the bushing 6. If no spark passes, it indicates that no spark is being formed between the wire points at 4.

80 It will be seen that the passage of the electric current is thus tested on the ground side of the circuit with respect to the points 4, so that the presence of a spark between the point 16 of the sleeve 14, and the bushing 6, indicates that the current has jumped over the gap between the points 4, making a more certain test than where the test is made on the positive side of the circuit, with respect to the points 4, in which latter case 90 various short-circuits to ground would permit the current to pass the testing device without passing between the points at 4.

95 What we claim as new and desire to secure by Letters Patent is:

A spark-plug comprising a wire-holder of insulating material; a metal casing for the inner portion of the wire-holder adapted to engage a spark-plug-aperture in an engine-casing in electrical connection with the 105 ground side of an electric circuit; two wires in said wire-holder, terminating in adjacent points at the inner end of the plug, one of said wires extending longitudinally through the holder and having an outwardly pro- 110

jecting end adapted to be connected with the other side of said electric circuit, the other of said wires having its outer end projecting laterally through, and being exposed 5 upon one side of the wire-holder outside of said wire-holder-casing; and a metal sleeve movably mounted in contact with said laterally projecting exposed end of said last-

named wire on the wire-holder outside of said wire-holder-casing, and movable into 10 and out of contact with said metal-casing.

In testimony whereof we have hereunto set our hands this 10th day of July, 1916.

WILLIAM F. LAUGHRAN.
FRANK C. ALARIE.
